CLAIM

The ornamental design for a combined socket and connector housing for an automotive lamp assembly, as shown and described.

DESCRIPTION

FIG. 1 is a front and upper left perspective view of a combined socket and connector housing for an automotive lamp assembly showing our new design. The broken line illustration of the lamps is included for the purpose of illustrating environmental elements that form no part of the claimed design;

FIG. 2 is a front elevational view thereof;

FIG. 3 is a left end elevational view thereof;

FIG. 4 is a right end elevational view thereof;

FIG. 5 is a bottom plan view thereof; and,

FIG. 6 is rear elevational view thereof.

FIG. 1

FIG. 3

FIG. 2

FIG. 4

FIG. 5

FIG. 6
